UNITED STATES PATENT OFFICE.

JOHN M. SAUDER, OF HARRISBURG, PENNSYLVANIA.

SCHOOL-DESK.

SPECIFICATION forming part of Letters Patent No. 331,549, dated December 1, 1885.

Application filed March 23, 1885. Serial No. 159,786. (No model.)

To all whom it may concern:

Be it known that I, JOHN M. SAUDER, of Harrisburg, in the county of Dauphin and State of Pennsylvania, have invented certain new and useful Improvements in School-Seats, of which the following is a full, clear, and exact description.

Reference is to be had to the accompanying drawings, forming part of this specification, in which similar letters of reference indicate corresponding parts in all the figures.

Figure 1, Sheet 1, is a side elevation of one of my improved school-seats, and showing in dotted lines the seat folded. Fig. 2, Sheet 1, is a side elevation of the rear part of the seat-arm and the upper part of the seat-standard, the spring cap-plate being removed. Fig. 3, Sheet 1, is a side elevation of the rear part of the seat-arm. Fig. 4, Sheet 1, is a side elevation of the inner side of the upper end of a seat-standard. Fig. 5, Sheet 1, is a side elevation of the seat, showing the joints between the wooden strips. Fig. 6, Sheet 1, is a sectional plan view of the seat-arm, seat-standard, and cap-plate, taken through the line $x-x$, Fig. 1. Fig. 7, Sheet 1, is a sectional plan view of the seat-arm, taken through the line $x-x$, Fig. 1, being the same section as in Fig. 6. Fig. 8, Sheet 1, is a sectional plan view of the seat-standard, taken through the line $x-x$, Fig. 1, being the same section as in Fig. 6. Fig. 9, Sheet 1, is a side elevation of the spring cap-plate. Fig. 10, Sheet 1, is a sectional plan view of the same, taken through the line $y-y$, Fig. 9. Fig. 11, Sheet 2, is an under side view of a part of the seat, showing the locking-groove. Fig. 12, Sheet 2, is a perspective view of the locking-flange of the seat-arm. Fig. 13, Sheet 2, is the same view as Fig. 11, but showing a modification in the form of the locking-groove. Fig. 14, Sheet 2, is a perspective view of a modified form of the locking-flange of the seat-arm. Fig. 15, Sheet 2, is a sectional elevation of a part of the seat and of the locking-flange of the seat-arm.

The object of this invention is to provide school-seats constructed in such a manner that the parts can be readily put together, and will be held securely in place, and will allow the seat to be readily and noiselessly folded and extended.

The invention relates to a school-seat con-

structed with the end of the seat-standard made with a rounded recess, a curved slot, a curved groove, a spring-receiving recess, and a curved rounded recess, and connected with the end of the seat-arm made with a rounded projection and stop projections by a spring cap-plate and fastening-bolts, whereby is produced a firm and strong joint, working easily and without noise. The upper parts of the end frames and the seat-arms are provided with tongues having tapered dovetailed projections upon one or both sides, to engage with grooves in the seat and back provided with tapering enlargements, so that the said seat and back will be held firmly in place. The seat and back are made of wooden strips having two rounded grooves, two rounded tongues, and two square shoulders in each adjacent edge, so that close joints will be formed whether the said strips be arranged in a plane or a curve, as will be hereinafter fully described and then claimed.

A represents the end frame of a school-seat, which has a recess, B, in its forward edge, to receive the rear edge of the seat when folded, and to form a standard, C, to support the seat-arm D. Upon the side of the rear end of the seat-arm D are formed a rounded central boss, E, and two projections, F G, upon the rear and forward sides of and at a little distance from the said central boss, E. The central boss, E, fits into a corresponding recess, H, in the adjacent face of the upper end of the seat-standard C and works as a universal joint. The rear projection, F, works in a curved slot, I, in the side of the said upper end of the seat-standard C, and the forward projection, G, works in a curved groove, J, in the said side. In a recess, K, in the face of the side of the upper end of the seat-standard, at the lower end of the groove J, is placed a steel spring, L, with the upper end of which the projection G comes in contact when the seat is turned down into position for use, so that the said seat will come to its bearings gradually and without noise.

The upper end of the seat-standard C is kept in place against the rear end of the seat-arm D by a spring cap-plate, M, which is made with an inward projection, N, to fit into a curved recess, O, in the adjacent side of the upper end of the said seat-standard, as shown

in Fig. 6, so that the cap-plate M will act as a spring to gradually arrest the downward movement of the seat. The spring cap-plate M has holes in its front and rear ends to receive the bolts P, by which it is secured to the seat-arm D, the rear bolt P passing through the projection F, placed in the slot I of the seat-standard C. The seat and back are formed of wooden strips Q, the adjacent edges of which have two rounded tongues, R, two rounded grooves, S, and two narrow square shoulders, T, formed in each edge, so that when the said strips Q are clamped together the surplus glue will be pressed out and the wood at the shoulders T will be compressed, so that firm, strong, and close joints will be formed even when the strips are arranged to form a curve in the said seat or back.

In the under side of the seat and the rear side of the back, near their ends, are formed grooves U, which are made with a series of tapered or wedge-shaped enlargements, V, upon both sides, and are undercut or dovetailed on both sides, as shown in Figs. 11 and 25 15, or upon one side, as shown in Fig. 13.

Upon the upper edges of the seat-arms D and the forward edges of the upper parts of the end frames, A, are formed tongues W, which are made with tapered dovetailed projections X, made of such a size as to enter the enlargements V of the grooves U, and fit into the dovetailed parts of the said grooves between the said enlargements, as shown in Fig. 15. The dovetailed projections X can be formed upon both sides of the tongues W, as shown in Figs. 12 and 15, or upon only one side, as shown in Fig. 14, as may be desired.

Upon the sides of the dovetailed parts of the tongues W are formed small ribs Z, which are slightly inclined downward in such a direction that when the seat and back are driven

into place the said ribs will engage with the wood and draw the said seats and backs down firmly upon the shoulders of the castings.

In applying the seats and backs they are placed upon the tongues W in such positions that the enlargements V of the grooves U will receive the projections X of the said tongues W, and are then forced forward into place, bringing the said dovetailed and tapered projections into the dovetailed parts of the said grooves, so that the said seats and backs will be held firmly in place.

The seats and backs are driven home against shoulders Y, formed upon the ends of the said tongues W.

Having thus described my invention, what I claim as new, and desire to secure by Letters Patent, is—

1. In a school-seat, the combination, with the end of the seat-standard C, having rounded recess H, curved slot I, curved groove J, and curved rounded recess O, of the end of the seat-arm D, having rounded projection E, and stop projections F G, the spring cap-plate M, having rounded projection N, and the fastening-bolts P, substantially as herein shown and described, whereby is produced a firm and strong joint, working easily and without noise, as set forth.

2. In a school-seat, the combination, with the end of the seat-standard C, having rounded recesses H, curved slot I, curved groove J, spring-receiving recess K, having spring L, and curved rounded recess O, of the end of the seat-arm D, having rounded projection N, and the fastening-bolts P, substantially as and for the purpose set forth.

JOHN M. SAUDER.
